UNITED STATES PATENT OFFICE.

WILLIAM H. MILLER, OF CRAWFORDSVILLE, INDIANA, ASSIGNOR TO MILLER VEHICLE
HEATER COMPANY, OF CRAWFORDSVILLE, INDIANA, A CORPORATION OF INDIANA.

VEHICLE-HEATER.

1,164,841.

Specification of Letters Patent.

Patented Dec. 21, 1915.

Application filed November 14, 1913. Serial No. 800,991.

To all whom it may concern:

Be it known that I, WILLIAM H. MILLER, a citizen of the United States, residing at Crawfordsville, in the county of Montgomery and State of Indiana, have invented a new and useful Vehicle-Heater, of which the following is a specification, reference being had to the accompanying drawings and to the letters and figures of reference 10 marked thereon.

This invention relates to the type of heating apparatus that is adapted to be used for various purposes, and especially adapted to be connected to the bottom or floor 15 of various vehicles or rooms for heating the interior of the vehicles or rooms, by means of radiated heat and also heated air, the invention having reference more particularly to the structure and various parts 20 thereof described in my pending application for Letters Patent of the United States, filed July 28, 1913, Serial No. 781,551, and also to improvements in the apparatus.

An object of the invention is to provide 25 heating apparatus that shall be adapted to be attached to floors of buildings or vehicles of various types, such as wagons, omnibuses, carriages or the like.

Another object of the invention is to provide 30 heating apparatus of simple construction which may be cheaply manufactured and readily set up for use.

A still further object is to provide a safety heater adapted more especially for 35 use in heating vehicles that are designed for conveying pupils to or from school, or for rural postal routes, which heater shall be so constructed as to not be liable to derangement and which shall be adapted for burning charcoal or wood which may usually be 40 obtained in any locality.

The invention consists in heating apparatus comprising a furnace having its upper portion exposed or uncovered so as to supply 45 directly radiated heat, there being air passages around the furnace so that air is heated and caused to circulate and escape for heating purposes, the invention consisting also in various novel features of construction 50 embraced in the apparatus, and

in the parts and combinations and arrangements of parts as hereinafter particularly described and claimed.

Referring to the drawings, Figure 1 is a front elevation of a heater constructed substantially in accordance with the invention; Fig. 2, a side elevation of the heater; Fig. 3, an enlarged vertical section approximately on the line A A in Fig. 1; Fig. 4, an enlarged transverse section approximately on the line B B in Fig. 2; Fig. 5, a section on the plane of the line C C in Fig. 4; Fig. 6, a section approximately on the line D D in Fig. 4 looking upward; Fig. 7, a perspective view of the heater front part; Fig. 8, 65 a perspective view of the back part of the fire box of the furnace, and Fig. 9 is a perspective view of one of the fire box wall linings.

Corresponding reference characters in the 70 different figures of the drawings indicate corresponding elements or features of construction herein referred to.

The improved heater being especially adapted to be arranged under and connected 75 with the floor of a compartment or the body of the vehicle or car in a particular manner, a floor is shown, of which the numeral 1 indicates the forward portion and 2 the rearward portion of a vehicle floor, a suitable opening 3 being made or left in the floor through which the heat may enter the body of the vehicle. The heater comprises a suitable casing or drum 4 which preferably is cylindrical and has heads 5 and 6 on opposite 80 ends thereof respectively, the normal upper portion of the head 6 having an aperture 7 therein to receive a draft pipe. The drum is longer than the opening in the floor and is arranged below the opening, the normal 85 upper portion of the casing or drum having an aperture 8 therein that is approximately equal in length longitudinally to the transverse diameter of the opening in the floor and less in width transversely than the longitudinal diameter of the opening in the floor, the casing or drum extending transversely relatively to the vehicle body in order that the heater may be conveniently 90 operated under the conditions to which it 100

may be subjected. The cylindrical portion of the casing or drum is composed of sheet metal and portions of the metal on opposite sides of the opening 8 are turned upward and outward flaringly to form hangers 9 and 10 to which plates 11 and 12 are secured respectively so as to extend radially from the casing, the plates extending through the opening 3 and having flanges 13 and 14 formed thereon that extend outward for support upon the vehicle floor, the flanges being suitably secured to the floor, other portions of the metal being turned upward to form hangers 15 and 16 at opposite ends of the opening 8 respectively, two V-shaped plates 17 and 18 being secured to the hangers 15 and 16 and to the plates 11 and 12 so as to complete an air-outlet or distributing duct, the plates 17 and 18 having flanges 19 and 20 thereon respectively that extend outward for support upon the vehicle floor. The outlet orifice of the duct is covered by a grating or register 21 arranged upon the flanges of the duct and suitably secured in place.

Preferably the head or front 5 is formed as a casting and it has an annular flange or rib 22 on its inner side and extending into the forward end of the cylindrical casing, being provided with suitable bolt holes 23, 23', that receive securing bolts 24, 24', inserted through the wall of the casing whereby the head is fixedly secured to the casing. The front has also another annular rib 25 on the inner side thereof that is smaller in diameter and concentric to the flange or rib 22. The normal upper portion of the front has a doorway 26 therein adapted to receive fuel, the front being provided at one side of the doorway with suitable hinge ears 27. A door 28 is provided which has hinge ears 29 on one side thereof connected to the ears 27 by vertically arranged hinge pins 30, the front having a catch 31 adjacent to the opposite side of the doorway. A latch bar 32 is connected to the door by means of a pivot 33 and is provided with a handle or knob 34 for connecting the latch bar with the catch 31 or disconnecting it therefrom. The normal lower portion of the front 5 has an aperture or doorway 35 therein above which a horizontal ledge 36 is formed on the inner side of the front and integral with the rib 25 for supporting a fire-grate, the front having bolt holes 37 and 37' therein above the ledge 36 and adjacent to the inner side of the rib 25, a door frame 38 being formed on the outer side of the front 5 and extending about the aperture 35, the front of the door frame being sloping. The front 5 is provided also with hinge ears 39 above the door frame, an ash pit door or damper 40 being provided for closing the aperture 35 and having hinge ears 41 that are connected by means of hori-

zontal hinge pins 42 to the ears 39, the door 40 falling by gravity and normally resting on the frame 33. The door 40 is provided on its free end with a lateral arm 43 that extends below the hinges of the fire-door 28, a chain or cable 44 being connected to the arm for opening the door 40, and for holding the door in partially open position for regulating the draft required for combustion of the fuel. The opposite head 6 may suitably be composed of sheet metal and it may be secured to the casing or drum 4 by any suitable or desired means.

The fire box of the heater comprises a hollow cylinder 45 and one end portion thereof extends around the rib 25 and abuts the inner side of the head or front 5, the latter constituting the front of the fire-box as well as the adjacent wall of the air passage between the casing 4 and the fire-box wall. The cylinder 45, as will be seen, extends under the distributing duct so that the latter receives the heat that may be radiated directly from the upper portion of the fire box, the fire-box including a rear plate or wall 46 which has an annular flange or rib 47 on its inner side and extending into the opposite or rear end portion of the cylinder 45, the latter being of suitable length so as to extend toward but not entirely to the head 6. The inner side of the wall 46 is provided with a ledge 48 that extends on one and the same plane with the ledge 36 and is formed integral with the flange or rib 47 for supporting the fire-grate. The wall has bolt holes 49 therein above the ledge and adjacent to the inner side of the rib 47. The normal top portion of the wall 46 has an extension or ear 50 thereon that projects beyond the cylinder 45 and has a bolt hole 51 therein. Two securing bolts or rods 52 and 53 extend along the opposite portions of the interior of the fire-box adjacent to the cylinder 45 and are connected to the front or head 5 and also to the rear wall 46, the rods being received in the bolt holes formed in the heads, so that the rods are arranged slightly above the ledges 36 and 48. A similar bolt or rod 54 is connected to the upper portion of the front or head 5 and extends along the top of the cylinder 45 and is connected to the ear 50. The bolts or rods tightly hold the cylinder to the front and the rear wall of the cylinder. The upper portion of the rear wall 46 has a draft-opening 55 therein from which extends a draft pipe 56 through the aperture 7. The plate or wall 46 and the draft pipe 56 preferably are formed as a single casting and the upper portion of the draft pipe preferably has a pin-hole 57 therein to receive a pin whereby to secure a draft pipe extension to the draft pipe 56, the latter being suitably secured to the head 6, preferably by means of a collar 58 secured to

the outer side of the head 6 and having a flange or projection 59 thereon which is secured by means of a bolt 60 to the draft pipe.

The fire-box is provided with two lining plates 61 and 62 in order to protect the cylinder 45, the plates extending from the front 5 to the back wall 46 and resting upon the ledges 36 and 48, the plates being inclined so that they extend upward divergently. The 10 plates are cast from one pattern so as to be interchangeable and the outer sides of the plates have horizontal grooves or flutings 63 and 63' respectively, two of the grooves receiving the rods 52 and 53 which hold the 15 plates slightly apart from the cylinder 45 adjacent to the ledges. The upper portions of the plates are secured to opposite portions of the cylinder 45 by means of bolts 64 and 64' respectively, each plate having a suitable 20 number of bolt holes 65 therein to receive the bolts. The lower portions of the plates have vertical faces 66 and 66' respectively that serve as guides for grate bars 67 which are cast integrally with cross-bars 68 25 and 69 that rest upon the ledges 36 and 48 respectively.

The normal under portion of the casing or drum 4 has a longitudinally arranged row of air-inlet openings 70 and a parallel 30 row of similar openings 71, the portion of the casing that is forward relative to the vehicle being provided with hinge devices 72 provided with a hinge pin 73. A curved regulating door 74 corresponding to the curvature of the casing is provided and has a hinge device 75 which is connected to the hinge pin 73. When the regulating door is drawn against the casing it closes all the inlet openings, but when it is lowered 35 slightly one of the rows which is nearest the hinge pin is uncovered to a less extent than the openings farther removed from the hinge connections. When the door is in partially opened position and the vehicle carrying 40 the heater is in motion so that air currents are produced, the door deflects the air so that cold air and dust are not drawn directly into the air-inlet openings, the dust being deflected from the openings. The air-inlet 45 openings, 70, 71, are relatively large so that dust or trash falling through the grating 21 may escape from the casing. In order to govern the admission of air, the door 74 is provided with a projecting finger 76 to 50 which a chain or cable 77 is connected so that the door may be permitted to open by gravity and its movement be controlled.

In some cases more heat than desired may be passing through the grating 21 after 55 checking the fire, and in order to temper the heat the opposite upper portions of the casing or drum 4 are provided with two rows of cold-air-inlet apertures 78 and 79 respectively adjacent to the hanger portions 9 and

10 respectively, and suitable hinge devices 65 80 and 80' are secured to the casing and provided with hinge pins 81 and 81' respectively, two valves 82 and 83 being provided and adapted to normally close the two rows of apertures respectively, the valves being 70 fitted to the exterior of the casing or drum and having hinge devices 84 and 85 that are connected to the hinge pins 81 and 81' respectively. The valves 82 and 83 are provided respectively with beads 86 and 87 on 75 the outer sides of their free ends and also with lugs 88 and 89 to which two chains 90 and 91 are respectively connected, the chains being brought up over the top of the casing and connected to a chain or cable 92, so that 80 both of the valves may be opened at one operation. In order to limit the extent of opening of the valves and to promptly close them, two leaf springs 93 and 94 are secured to the outer side of opposite portions of the 85 casing 4 and extend upward at the outer side of the valves, the springs having suitably shaped bearing portions 95 and 96 respectively adapted to permit sliding contact of the beaded ends of the valves therewith for 90 forcing the valves to closed position, the ends of the springs having crooks 97 and 98 thereon respectively against which the beads are stopped when the valves are opened to the required extent for uncovering the inlet 95 apertures.

In order to prevent radiation of heat to the atmosphere from the relatively thin casing and distributing duct, a lining 99 is suitably secured to the inner side of one portion and a similar lining 99' on the opposite inner portion of the casing 4, linings 100 and 100' being secured to the inner sides of the plates 11 and 12 respectively, a lining 101 being secured to the inner side of the head 6, 100 other linings 102 and 103 being secured to the inner sides of the plates 17 and 18 respectively. The linings may suitably be composed of sheet asbestos or other non-combustible substance presenting a smooth 110 face so that dust gravitating through the air passages shall not adhere thereto but pass on and out through the air-inlet openings 70 and 71 and thence down over the inclined door 74. 115

It will be observed that the controlling chains or cables 44, 77 and 92 are so arranged that they may be readily brought up or guided to one and the same station, in order that full and convenient control of the heating apparatus may be had.

In practical use, the fuel is inserted through the doorway 26 and the fire is regulated so as to control the heat by adjusting the door or draft regulator 40. The ashes 125 resulting from combustion fall through the fire grate and to the under portion of the cylinder 45 and are removed through the

doorway 35. The smoke, if any, and gases resulting from combustion are drawn through the draft pipe 56. The upper portion of the cylinder 45 becomes heated and the heat is radiated directly through the distributing duct to and through the grating 21 which becomes sufficiently heated to warm the feet of those standing upon it. Atmospheric air is admitted into the casing below 10 the fire box through the air-inlet openings 70 and 71 by means of the door 74, and the air in passing upward around the sides of the fire box becomes heated and is to an extent superheated by the upper portion of the fire box cylinder, the circulating air partaking of the directly radiated heat, the heated air rising through the openings in the grating 21. The fire box, as will be seen, is relatively large so that the fire need not be forced and a high degree of heat is obtained with a relatively low rate of combustion, and therefore the fuel need not be frequently replenished, the heater therefore being adapted to be operated economically.

25 In case less heat is desired after the fire is checked, the chain 92 is pulled upward so as to open the valves 82 and 83 which permit cold air to enter and temper the heat passing up the distributing duct, the cooler air also furnishing refreshing breathing air for the occupants of the room or chamber above.

30 Having thus described the invention, what is claimed as new is—

35 1. In a heater, the combination of a normally horizontal cylindrical casing having an outlet-opening in its upper portion and having also an air-inlet aperture adjacent to the outlet-opening, the under portion of the casing having an air-inlet therein, a curved door movably mounted on the under portion of the casing to cover the air-inlet, a cylindrical fire-box supported in the casing between the air-inlet and the outlet-opening, the fire-box extending opposite the aperture, 40 a fire-door connected with the fire-box, a fire-grate supported in the fire-box, and a curved air-inlet valve pivotally mounted on the casing adjacent to the outlet-opening and adapted for closing the air-inlet aperture.

45 2. In a heater, the combination of a normally horizontal cylindrical casing having a distributing duct connected to its upper portion and having also air-inlet apertures in its upper portion on opposite sides respectively of the duct, the under portion of the casing having an air-inlet therein provided with a curved and swinging regulating door, a cylindrical fire-box 50 supported horizontally in the casing and extending opposite the air-inlet and the apertures and also under the duct, a fire-door connected with the fire-box, and a pair of curved air-regulating valves hinged to

the upper portion of the casing adjacent to 65 opposite sides respectively of the duct and adapted to swing down to close the air-inlet apertures respectively, each valve being provided with a controlling device.

3. In a heating apparatus, the combination 70 of a horizontal cylindrical casing having air-inlet openings in the under portion and a plurality of air-inlet apertures in the upper portion thereof, a duct connected to the upper portion of the casing above the 75 apertures, a valve hinged to the casing above and extending down over the apertures, a spring for closing the valve, a chain connected to the valve for opening it, and a fire-box supported in the casing opposite the 80 openings and the apertures.

4. In a heating apparatus, the combination 85 of a front, a horizontal casing connected to the front and having an air-inlet opening in the under portion thereof, a head secured to the casing and having an aperture in the upper portion thereof, a collar secured to the outer side of the head and extending about the aperture, the collar having a projection thereon, a distributing duct 90 connected to the upper portion of the casing a fire-box cylinder connected to the front and extending under the duct and toward the head, a back plate connected to the end of the cylinder and having a 95 draft pipe thereon extending through the aperture in the head and also through said collar, and means for securing the draft pipe to said projection.

5. In a heating apparatus, the combination 100 of a fire-box cylinder a casing extending about the cylinder and having an air-inlet in its under portion, a head and a back plate connected to opposite ends respectively of the cylinder and having each a ledge on 105 the inner side thereof, the back plate having a draft pipe, a distributing duct connected to the upper portion of the casing, a rod connected to the head and also to said back plate, two lining plates and also a fire-grate 110 supported by the ledges, the backs of the lining plates having longitudinal grooves therein, bolts securing the lining plates to the cylinder, and two rods extending in the grooves of the two lining plates respectively 115 and connected to the head and also to the back plate.

6. In a heating apparatus, the combination 120 of a horizontal cylindrical fire-box, a cylindrical casing extending about and supporting the fire-box and having air-inlet openings in the under portion thereof below the fire-box, the upper portion of the casing having a plurality of apertures therein arranged in two separate longitudinal rows, a 125 distributing duct connected to the casing between the two rows of apertures, two curved valves hinged to the casing above the

two rows of apertures respectively and extending downward over the apertures, each valve having a bead and also projecting lugs thereon, a spring secured to the casing below 5 each of said valves respectively and extending upward to the valves, each spring having a crook to be engaged by the bead of the adjacent valve, two chains connected re-

spectively to the lugs, and a pull chain connected to the two chains.

In testimony whereof I affix my signature in presence of two witnesses.

WILLIAM H. MILLER.
